PILOT LIGHT LENS

Kenneth J. Marien, Milwaukee, and Joseph J. Gribble,
Fox Point, Wis., assignors to Square D Company, Park
Ridge, Ill., a corporation of Michigan

Filed June 9, 1960, Ser. No. 60,902

Term of patent 14 years

(Cl. D26—13)

FIG. 1

FIG. 2

FIG. 3

FIG. 4

FIG. 1 is a front perspective view of a pilot light lens in an electrical switch enclosure, showing our new design;
FIG. 2 is a front elevational view thereof;
FIG. 3 is a side elevational view thereof; and
FIG. 4 is a top plan view thereof.

The broken line showing is for illustrative purposes only.

We claim:

The ornamental design for a pilot light lens, substantially as shown and described.
